UNITED STATES PATENT OFFICE.

JOHN A. MITCHELL, OF LUDINGTON, MICHIGAN.

PIER OR BREAKWATER.

No. 881,605.

Specification of Letters Patent. Patented March 10, 1908.

Application filed April 18, 1907. Serial No. 369,011.

To all whom it may concern:

Be it known that I, JOHN A. MITCHELL, a citizen of the United States, residing at the city of Ludington, county of Mason, State of Michigan, have invented certain new and useful Improvements in Piers or Breakwaters, of which the following is a specification.

This invention relates to improvements in piers, breakwaters, or the like.

10 The main objects of this invention are, first, to provide an improved artificial stone or concrete pier or breakwater, or similar structure, in which a comparatively small amount of material is used in its construction, and one which is at the same time capable of withstanding very severe strains and is very strong and durable; second, to provide an improved pier or like structure which is simple and economical in construction and at the same time strong and durable; third, to provide an improved pier or like structure in which the danger of damage or loss during the process of construction is comparatively slight; fourth, to provide an improved pier or like structure which may be made up of units or sections, and one which is, when completed, practically an integral structure; and fifth, to provide an improved combination foundation pile and substructure for piers and like structures.

Further objects, and objects relating to details of construction, will definitely appear from the detailed description to follow.

35 I accomplish the objects of my invention by the devices and means described in the following specification.

The invention is clearly defined and pointed out in the claims.

40 A structure embodying the features of my invention is clearly illustrated in the accompanying drawing, forming a part of this specification, in which,

Figure 1 is a detail front elevation of a structure embodying the features of my invention; Fig. 2 is a detail vertical section therethrough corresponding to line 2—2 of Fig. 1; Fig. 3 is a detail horizontal section taken on a line corresponding to line 3—3 of Fig. 2; Fig. 4 is a detail longitudinal vertical section through the substructure taken on a line corresponding to line 4—4 of Fig. 2; Fig. 5 is a horizontal section corresponding to that of Fig. 3, of a modified construction, 55 the central posts being formed substantially the same as the side wall sections and adapt-

ed to form a continuous central wall, the form of the wall sections also being somewhat modified, the guiding shoulders 10 being provided instead of forming the edges of 60 the side wall sections to engage; and Fig. 6 is a view corresponding to that of Fig. 5 of a further modification.

In the drawings, similar numerals of reference refer to similar parts throughout the 65 several views, and the sectional views are taken looking in the direction of the little arrows at the ends of the section lines.

Referring to the drawing, the substructure of my improved pile, breakwater, or the like 70 is formed of sections or units 1, comprising side wall sections 3, united by cross-beams 4. The units are preferably further strengthened by central posts 3' to which the cross-beams are connected. These wall sections and 75 posts are preferably extended into foundation piles 2. The units are preferably strengthened and reinforced by metal frames 5, made up of vertical pieces connected by cross-pieces embedded in the side wall sections and cross-beams, the reinforcing strips 80 also extending into the foundation piles. In the preferred construction, pipes 9 are embedded in the central posts, the pipes extending from the top to the bottom thereof. 85

One edge of each section is in the preferred construction made **A**-shaped as at 7, and the other **V**-shaped as at 6, so that the sections are guided and held in alinement in placing. Each edge of the wall sections is provided 90 with a channel or groove 8 extending from the top to the bottom thereof, these channels or grooves being adapted to register when the sections are in position. After placing the units in position these channels 95

or grooves are filled with cement or concrete thereby forming a cement joint or bond and making the walls practically solid and continuous and substantially water and sand tight. These channels are of further advantage in placing the piles, as the jet hose for forcing away the sand to settle the units in place may be introduced through these openings so that it is delivered at the most effective point. The lower ends of the pile members 2 are preferably inclined rearwardly and downwardly, so that the tendency in settling 105 is to draw them against the unit already in place. The pipes 9 of the central post also serve as a means for introducing the water jets for settling the units into place. The cement or concrete may be conveniently in- 110

roduced into the channels for forming the joints or bonds between the units by placing the same in sacks of such size that they may be readily dropped or rammed into place.

5 When the joint is set the units are firmly united, forming, as stated, a continuous wall.

In the modified construction shown in Fig. 5 the channels are formed somewhat in the shape of key-hole slots, so that the joint has

10 a somewhat more secure hold upon the units.

In this construction, instead of forming the edges of the wall sections to engage each other, guide shoulders 10 are provided. In this construction the central posts are adapt-

15 ed to form a continuous central wall which may be of advantage in piers of large size.

In the modified construction shown in Fig. 6 the edges of the wall sections are somewhat further modified, their edges being inclined

20 inwardly so that the tendency is to properly center the units upon those already in place.

It is intended that the substructure shall project slightly above the water line as is common with structures of this class. The

25 superstructure is also preferably formed of concrete and comprises the front wall 11, central wall or beam 12, rear wall 13, and central posts 12', see Figs. 2 and 4, by which the flooring or deck is supported. These

30 front and rear walls, central posts, and deck are preferably formed integral of concrete and molded upon the substructure, having tongues 14 which engage the channels 15 in the upper ends of the units. This further

35 secures the units in place and effectively secures the superstructure upon the substructure. The deck 16 is provided with man-hole openings 17 through which the filling material may be introduced. I preferably

40 use sand for this filling material, as the outer walls being practically continuous effectively hold the sand, and it may be conveniently introduced by means of a pump or the like, and with the manhole covers 18 in place, the

45 inside of the pier or breakwater is a closed chamber. The front wall of the superstructure preferably projects above the floor or deck and may be provided with suitable abutments, as required. As these form no

50 part of this invention, they are not here illustrated. By thus forming the parts a pier or like structure may be constructed with a minimum amount of material, and at the same time be capable of withstanding very

55 severe strains and shocks. It will be evident that it is thoroughly braced so that the strain, as, for instance, that of the water impact, is withstood by the strength of the whole structure. The units are readily

60 placed in position so that the building may be rapidly carried on and as the substructure is practically completed as rapidly as the units are put in place, and the concrete or cement for the joints has an opportunity

65 of setting, the danger from loss by storms

during the building operation is reduced to a minimum. On account of the solid or continuous feature of the walls the pier may be filled with sand and effectively retain the same. It is intended that the units shall be 70 built on shore and transferred to the pier as they are placed.

While I prefer to provide a concrete superstructure, as illustrated and described, other forms may be used and desirable results will 75 be secured. I also prefer to form the substructure and the piles integral, although the substructure is of advantage for locating upon a foundation formed of wooden piles or other suitable material.

I have illustrated and described my improved pier construction in the form preferred by me on account of its structural simplicity and economy. I am, however, aware that it is capable of considerable or very 80 great variation in structural details without departing from my invention, and I desire to be understood as claiming the same specifically, as illustrated, as well as broadly.

Having thus described my invention, what 90 I claim as new and desire to secure by Letters Patent, is:

1. In a structure of the class described, the combination of a plurality of integral foundation and substructure units or sections 95 formed of concrete, each unit comprising side wall sections and a post connected by cross beams, said side wall sections and post being extended into foundation piles the lower ends of which are inclined downwardly 100 and rearwardly, said wall sections being A-shaped on one edge and V-shaped on the other, the edges of said wall sections also having longitudinal channels extending from the top to the bottom thereof, said channels 105 being adapted to register when the units are in position, said units also having horizontal channels in their upper ends; a concrete filling for said channels in the edges of said wall sections forming a bond for said units; pipes 110 embedded in said posts of said units and extending from the tops to the bottoms thereof; and a superstructure comprising a deck having manholes therethrough, front and rear walls, and central posts formed integral 115 of concrete and molded upon said substructure, said front and rear walls and central posts of said superstructure having tongue projections molded into the said channels in the upper ends of said units, whereby the units are further united and said superstructure secured in position thereon, for the purpose specified.

2. In a structure of the class described, the combination of a plurality of integral foundation and substructure units or sections formed of concrete, each unit comprising side wall sections and a post connected by cross beams, said side wall sections and post being extended into foundation piles the 130

lower ends of which are inclined downwardly and rearwardly, said wall sections being **A**-shaped on one edge and **V**-shaped on the other, the edges of said wall sections also 5 having longitudinal channels extending from the top to the bottom thereof, said channels being adapted to register when the units are in position, said units also having horizontal channels in their upper ends; a concrete filling 10 for said channels in the edges of said wall sections forming a bond for said units; and a superstructure comprising a deck having manholes therethrough, front and rear walls, and central posts formed integral of concrete and molded 15 and molded upon said substructure, said front and rear walls and central posts of said superstructure having tongue projections molded into the said channels in the upper ends of said units, whereby the units are further united 20 and said superstructure secured in position thereon, for the purpose specified.

3. In a structure of the class described, the combination of a plurality of integral foundation and substructure units or sections and a post connected by cross beams, said side wall sections and post being extended into foundation piles, said wall sections being **A**-shaped on one edge and **V**-shaped on the other, the edges of said wall sections also 25 having longitudinal channels extending from the top to the bottom thereof, said channels being adapted to register when the units are in position; a concrete filling for said channels in the edges of said wall sections forming a bond for said units; and pipes embedded 30 in said posts of said units and extending from the tops to the bottoms thereof, for the purpose specified.

35 channels in their upper ends; a concrete filling for said channels in the edges of said wall sections forming a bond for said units; pipes embedded in said posts of said units and extending from the tops to the bottoms thereof; and a superstructure comprising a deck having manholes therethrough, front and rear walls, and central posts formed integral of concrete and molded upon said substructure, said front and rear walls and central 40 posts of said superstructure having tongue projections molded into the said channels in the upper ends of said units, whereby the units are further united and said superstructure secured in position thereon, for the purpose specified.

4. In a structure of the class described, the combination of a plurality of integral foundation and substructure units or sections formed of concrete, each unit comprising 45 side wall sections and a post connected by cross beams, said side wall sections and post being extended into foundation piles, said wall sections being **A**-shaped on one edge and **V**-shaped on the other, the edges of said 50 wall sections also having longitudinal channels extending from the top to the bottom thereof, said channels being adapted to register when the units are in position, said units also having horizontal channels in their upper ends; a concrete filling for said chan-

nels in the edges of said wall sections forming a bond for the units; and a superstructure comprising a deck having manholes therethrough, front and rear walls, and central posts formed integral of concrete and molded 70 and upon said substructure, said front and rear walls and central posts of said superstructure having tongue projections molded into the said channels in the upper ends of said units, whereby the units are further united 75 and said superstructure secured in position thereon, for the purpose specified.

5. In a structure of the class described, the combination of a plurality of integral foundation and substructure units or sections 80 formed of concrete, each unit comprising side wall sections and a post connected by cross beams, said side wall sections and post being extended into foundation piles the lower ends of which are inclined downwardly and rearwardly, said wall sections being **A**-shaped on one edge and **V**-shaped on the other, the edges of said wall sections also 85 having longitudinal channels extending from the top to the bottom thereof, said channels being adapted to register when the units are in position; a concrete filling for said channels in the edges of said wall sections forming a bond for said units; and pipes embedded 90 in said posts of said units and extending from the tops to the bottoms thereof, for the purpose specified.

6. In a structure of the class described, the combination of a plurality of integral foundation and substructure units or sections 100 formed of concrete, each unit comprising side wall sections and a post connected by cross beams, said side wall sections and post being extended into foundation piles the lower ends of which are inclined downwardly and rearwardly, said wall sections being **A**-shaped on one edge and **V**-shaped on the other, the edges of said wall sections also having longitudinal channels extending from the top to the bottom thereof, said channels being 105 adapted to register when the units are in position, and a concrete filling for said channels in the edges of said wall sections forming a bond for said units, for the purpose specified.

7. In a structure of the class described, the combination of a plurality of integral foundation and substructure units or sections formed of concrete, each unit comprising side wall sections and a post connected by cross 120 beams, said wall sections and post being extended into foundation piles the lower ends of which are inclined downwardly and rearwardly, said wall sections being **A**-shaped on one edge and **V**-shaped on the other, the edges of said wall sections also having longitudinal channels extending from the top to the bottom thereof, said channels being 125 adapted to register when the units are in position; a concrete filling for said channels 130

in the edges of said wall sections, forming a bond for said units, and pipes embedded in said posts of said units and extending from the tops to the bottoms thereof, for the purpose specified.

8. In a structure of the class described, the combination of a plurality of integral foundation and substructure units or sections formed of concrete, each unit comprising 10 side wall sections and a post connected by cross beams, said side wall sections and post being extended into foundation piles, said wall sections being A-shaped on one edge and V-shaped on the other, the edges of said 15 wall sections also having longitudinal channels extending from the top to the bottom thereof, said channels being adapted to register when the units are in position, and a concrete filling for said channels in the edges of 20 said wall sections forming a bond for said units, for the purpose specified.

9. In a structure of the class described, the combination of a plurality of integral foundation and substructure units or sections 25 formed of concrete, each unit comprising side wall sections and a post connected by cross beams, said side wall sections and post being extended into foundation piles, said wall sections having longitudinal channels 30 extending from the top to the bottom thereof, said channels being adapted to register when the units are in position, said units also having horizontal channels in their upper ends; a concrete filling for said channels in the 35 edges of said wall sections, forming a bond for said units; a metal reinforcing frame for each of said units made up of connected vertical and cross pieces embedded in said wall sections, and said cross beams; pipes embedded in said posts of said units and extending 40 from the tops to the bottoms thereof; and a superstructure comprising a deck having manholes therethrough, front and rear walls, and central 45 posts of concrete and molded upon said substructure, said front and rear walls and central posts of said superstructure having tongue projections molded into the channels in the upper ends of said units, whereby the units are further united and said 50 superstructure secured in position thereon, for the purpose specified.

10. In a structure of the class described, the combination of a plurality of integral 55 foundation and substructure units or sections formed of concrete, each unit comprising side wall sections and a post connected by cross beams, said side wall sections and post being extended into foundation piles, 60 said wall sections having longitudinal channels extending from the top to the bottom thereof, said channels being adapted to register when the units are in position, said units also having horizontal channels in their upper 65 ends; a concrete filling for said channels in

the edges of said wall sections, forming a bond for said units; pipes embedded in said posts of said units and extending from the tops to the bottoms thereof; and a superstructure comprising a deck having manholes therethrough, front and rear walls, and central posts formed integral of concrete and molded upon said substructure, said front and rear walls and central posts of said superstructure having tongue projections molded into the channels in the upper ends of said units, whereby the units are further united and said superstructure secured in position thereon, for the purpose specified. 70 75

11. In a structure of the class described, the combination of a plurality of integral foundation and substructure units or sections formed of concrete, each unit comprising side wall sections and a post connected by cross beams, said side wall sections and post being 80 extended into foundation piles, said wall sections having longitudinal channels extending from the top to the bottom thereof, said channels being adapted to register when the units are in position, said units also having horizontal channels in their upper ends; a concrete filling for said channels in the edges of 85 said wall sections, forming a bond for said units; a metal reinforcing frame for each of said units made up of connected vertical and cross pieces embedded in said wall sections and said cross beams; and a superstructure comprising a deck having manholes therethrough, front and rear walls, and central 90 posts formed integral of concrete and molded upon said substructure, said front and rear walls and central posts of said superstructure having tongue projections molded into the channels in the upper ends of said units, whereby the units are further united and said 95 superstructure secured in position thereon, for the purpose specified. 100 105

12. In a structure of the class described, the combination of a plurality of integral foundation and substructure units or sections 110 formed of concrete, each unit comprising side wall sections and a post connected by cross beams, said side wall sections and post being extended into foundation piles, said wall sections having longitudinal channels extending 115 from the top to the bottom thereof, said channels being adapted to register when the units are in position, said units also having horizontal channels in their upper ends; a concrete filling for said channels in the edges of said wall sections, forming a bond for said units; and a superstructure comprising a deck having manholes therethrough, front and rear walls, and central posts formed integral of concrete and molded upon said substructure, said front and rear walls and central posts of said superstructure having tongue projections molded into the channels in the upper ends of said units, whereby the units are further united and said superstruc- 120 125 130

ture secured in position thereon, for the purpose specified.

13. In a structure of the class described, the combination of a plurality of integral foundation and substructure units or sections formed of concrete, each unit comprising side wall sections and a post connected by cross beams, said side wall sections and post being extended into foundation piles, said wall sections having longitudinal channels extending from the top to the bottom thereof, said channels being adapted to register when the units are in position; a concrete filling for said channels in the edges of said wall sections, forming a bond for said units; a metal reinforcing frame for each of said units made up of connected vertical and cross pieces embedded in said wall sections and cross beams, and pipes embedded in said posts of said units and extending from the tops to the bottoms thereof, for the purpose specified.

14. In a structure of the class described, the combination of a plurality of integral foundation and substructure units or sections formed of concrete, each unit comprising side wall sections and a post connected by cross beams, said side wall sections and post being extended into foundation piles, said wall sections having longitudinal channels extending from the top to the bottom thereof, said channels being adapted to register when said units are in position; a concrete filling for said channels in the edges of said wall sections, forming a bond for said units, and pipes embedded in said posts of said units and extending from the tops to the bottoms thereof, for the purpose specified.

15. In a structure of the class described, the combination of a plurality of integral foundation and substructure units or sections formed of concrete, each unit comprising side wall sections and a post connected by cross beams, said side wall sections and post being extended into foundation piles, said side wall sections having longitudinal channels extending from the top to the bottom thereof, said channels being adapted to register when the units are in position; a concrete filling for said channels in the edges of said wall sections, forming a bond for said units, and a metal reinforcing frame for each of said units made up of connected vertical and cross pieces embedded in said wall sections and said cross beams, for the purpose specified.

16. In a structure of the class described, the combination of a plurality of integral foundation and substructure units or sections formed of concrete, each unit comprising side wall sections and a post connected by cross beams, said side wall sections and post being extended into foundation piles, said wall sections having longitudinal channels extending from the top to the bottom thereof, said channels being adapted to register when the units are in position, and a concrete filling for

said channels in the edges of said wall sections, forming a bond for said units, for the purpose specified.

17. In a structure of the class described, the combination of a plurality of substructure units or sections formed of concrete, each unit comprising side wall sections and a post connected by cross beams, said wall sections being **A**-shaped on one edge and **V**-shaped on the other, the edges of said wall sections also having longitudinal channels extending from the top to the bottom thereof, said channels being adapted to register when the units are in position, said units also having horizontal channels in their upper ends; a concrete filling for said channels in the edges of said wall sections, forming a bond for said units; pipes embedded in said posts of said units and extending from the tops to the bottoms thereof; and a superstructure of concrete molded upon said substructure, said superstructure having tongue projections molded into the said channels in the upper ends of said units, whereby the units are further united and said superstructure secured in position thereon, for the purpose specified.

18. In a structure of the class described, the combination of a plurality of substructure units or sections formed of concrete, each unit comprising side wall sections connected by cross beams, said wall sections being **A**-shaped on one edge and **V**-shaped on the other, the edges of said wall sections also having longitudinal channels extending from the top to the bottom thereof, said channels being adapted to register when the units are in position, said units also having horizontal channels in their upper ends; a concrete filling for said channels in the edges of said wall sections, forming a bond for said units; and a superstructure of concrete molded upon said substructure, said superstructure having tongue projections molded into the said channels in the upper ends of said units, whereby the units are further united and said superstructure secured in position thereon, for the purpose specified.

19. In a structure of the class described, the combination of a plurality of substructure units or sections formed of concrete, each unit comprising side wall sections and a post connected by cross beams, said wall sections being **A**-shaped on one edge and **V**-shaped on the other, the edges of said wall sections also having longitudinal channels extending from the top to the bottom thereof, said channels being adapted to register when the units are in position; a concrete filling for said channels in the edges of said wall sections, forming a bond for said units, and pipes embedded in said posts of said units and extending from the tops to the bottoms thereof, for the purpose specified.

20. In a structure of the class described,

the combination of a plurality of substructure units or sections formed of concrete, each unit comprising side wall sections connected by cross beams, said wall sections being 5 **A**-shaped on one edge and **V**-shaped on the other, the edges of said wall sections also having longitudinal channels extending from the top to the bottom thereof, said channels being adapted to register when the units are 10 in position, and a concrete filling for said channels in the edges of said wall sections, forming a bond for said units, for the purpose specified.

21. In a structure of the class described, 15 the combination of a plurality of substructure units or sections formed of concrete, each unit comprising side wall sections and a post connected by cross beams, said wall sections having longitudinal channels extending 20 from the top to the bottom thereof, said channels being adapted to register when the units are in position, said units also having horizontal channels in their upper ends; a concrete filling for said channels in 25 the edges of said wall sections, forming a bond for said units; pipes embedded in said posts of said units and extending from the tops to the bottoms thereof; and a superstructure of concrete molded upon said sub- 30 structure, said superstructure having tongue projections molded into the said channels in the upper ends of said units, whereby the units are further united and said superstructure secured in position thereon, for the pur- 35 pose specified.

22. In a structure of the class described, 40 the combination of a plurality of substructure units or sections formed of concrete, each unit comprising side wall sections connected by cross beams, said wall sections having longitudinal channels extending from the top to the bottom thereof, said channels being adapted to register when the units are in position, said units also having horizontal 45 channels in their upper ends; a concrete filling for said channels in the edges of said wall sections, forming a bond for said units; and a superstructure formed of concrete molded upon said substructure, said superstructure having tongue 50 projections molded into the said channels in the upper ends of said units, whereby the units are further united and said superstructure secured in position thereon, for the purpose specified.

23. In a structure of the class described, 55 the combination of a plurality of substructure units or sections formed of concrete, each unit comprising side wall sections and a post connected by cross beams, said wall 60 sections having longitudinal channels extending from the top to the bottom thereof, said channels being adapted to register when the units are in position; a concrete filling for said channels in the edges of said wall sections, forming a bond for said units, and 65

pipes embedded in said posts of said units and extending from the tops to the bottoms thereof, for the purpose specified.

24. In a structure of the class described, 70 the combination of a plurality of substructure units or sections formed of concrete, each unit comprising side wall sections connected by cross beams, said wall sections having longitudinal channels extending from the top to the bottom thereof, said channels 75 being adapted to register when the units are in position, and a concrete filling for said channels in the edges of said wall sections, forming a bond for said units, for the purpose specified.

25. In a structure of the class described, 80 the combination of a plurality of integral foundation and sub-structure units or sections formed of concrete, each unit comprising side wall sections and connecting cross-beams therefor, said side wall sections being extended into foundation piles, the lower ends of which are inclined downwardly and rearwardly, said side wall sections being **A**-shaped on one edge and **V**-shaped on the 85 other, the edges of said wall sections having longitudinal channels extending from the top to the bottom thereof, said channels being adapted to register when the units are in position, the said units also having horizontal 90 channels in their upper ends; a concrete filling for said channels in the edges of said wall sections forming a bond for the said units; and a superstructure of concrete molded upon said substructure, said superstructure having 95 tongue projections molded into said channels on the upper ends of said units whereby the units are further united and said superstructure secured in position thereon, for the purpose specified.

26. In a structure of the class described, 100 the combination of a plurality of integral foundation and substructure units or sections formed of concrete, each unit comprising side wall sections and connecting cross-beams therefor, said side wall sections being extended into foundation piles, the lower ends of which are inclined downwardly and rearwardly, said side wall sections being **A**-shaped on one edge and **V**-shaped on the 105 other, the edges of said wall sections having longitudinal channels extending from the top to the bottom thereof, said channels being adapted to register when the units are in position, and a concrete filling for said channels in the edges of said wall sections, forming a bond for the said units, for the purpose specified.

27. In a structure of the class described, 110 the combination of a plurality of integral foundation and sub-structure units or sections formed of concrete, each unit comprising side wall sections and connecting cross-beams therefor, said side wall sections being extended into foundation piles, said side 115

wall sections being **A**-shaped on one edge and **V**-shaped on the other, the edges of said wall sections having longitudinal channels extending from the top to the bottom thereof, said channels being adapted to register when the units are in position, the said units also having horizontal channels in their upper ends; a concrete filling for said channels in the edges of said wall sections forming a bond for said units; and a superstructure of concrete molded upon said substructure, said superstructure having tongue projections molded into said channels on the upper ends of said units whereby the units are further united and said superstructure secured in position thereon, for the purpose specified.

28. In a structure of the class described, the combination of a plurality of integral foundation and substructure units or sections formed of concrete, each unit comprising side wall sections and connecting cross-beams therefor, said side wall sections being extended into foundation piles and being **A**-shaped on one edge and **V**-shaped on the other, the edges of said wall sections having longitudinal channels extending from the top to the bottom thereof, said channels being adapted to register when the units are in position, and a concrete filling for said channels in the edges of said wall sections, forming a bond for the said units, for the purpose specified.

29. In a structure of the class described, the combination of a plurality of integral foundation and substructure units or sections formed of concrete, each unit comprising side wall sections and connecting cross-beams therefor, said side wall sections being extended into foundation piles, the lower ends of which are inclined downwardly and rearwardly, the edges of said wall sections having longitudinal channels extending from the top to the bottom thereof, said channels being adapted to register when the units are in position, the said units also having horizontal channels in their upper ends; a concrete filling for said channels in the edges of said wall sections forming a bond for the said units; and a superstructure of concrete molded upon said substructure, said superstructure having tongue-projections molded into said channels on the upper ends of said units, whereby the units are further united and said superstructure secured in position thereon, for the purpose specified.

30. In a structure of the class described, the combination of a plurality of integral foundation and substructure units or sections formed of concrete, each unit comprising side wall sections and connecting cross-beams therefor, said side wall sections being extended into foundation piles the lower ends of which are inclined downwardly and rearwardly, the edges of said wall sections

having longitudinal channels extending from the top to the bottom thereof, said channels being adapted to register when the units are in position, and a concrete filling for said channels in the edges of said wall sections, forming a bond for the said units, for the purpose specified.

31. In a structure of the class described, the combination of a plurality of integral foundation and substructure units or sections formed of concrete, each unit comprising side wall sections and connecting cross-beams therefor, said side wall sections being extended into foundation piles, the edges of said wall sections having longitudinal channels extending from the top to the bottom thereof, said channels being adapted to register when the units are in position, the said units also having horizontal channels in the edges of said wall sections forming a bond for said units; and a superstructure of concrete molded upon said substructure, said superstructure having tongue projections molded into said channels on the upper ends of said units whereby the units are further united and said superstructure secured in position thereon, for the purpose specified.

32. In a structure of the class described, the combination of a plurality of integral foundation and substructure units or sections formed of concrete, each unit comprising side wall sections and connecting cross-beams therefor, said side wall sections being extended into foundation piles, the edges of said wall sections having longitudinal channels extending from the top to the bottom thereof, said channels being adapted to register when the units are in position, and a concrete filling for said channels in the edges of said wall sections, forming a bond for the said units, for the purpose specified.

33. In a structure of the class described, the combination of a plurality of integral foundation and substructure units or sections formed of concrete, each unit comprising side wall sections and a post connected by cross beams, said side wall sections and post being extended into foundation piles; a concrete bond for the said units uniting them to form practically continuous solid side walls; and a superstructure of concrete molded upon said substructure, whereby said units are further united, for the purpose specified.

34. In a structure of the class described, the combination of a plurality of integral foundation and substructure units or sections formed of concrete, each unit comprising side wall sections and a post connected by cross beams, said side wall sections and post being extended into foundation piles, and a concrete bond for the said units uniting them to form practically continuous solid side walls, for the purpose specified.

35. In a structure of the class described, the combination of a plurality of integral foundation and substructure units or sections formed of concrete, each unit comprising side wall sections connected by cross beams, said side wall sections being extended into foundation piles; a concrete bond for the said units uniting them to form practically continuous solid side walls; and a superstructure of concrete molded upon said substructure, whereby said units are further united, for the purpose specified.

36. In a structure of the class described, the combination of a plurality of integral foundation and substructure units or sections formed of concrete, each unit comprising side wall sections connected by cross beams, said side wall sections being extended into foundation piles; and a concrete bond for said units uniting them to form practically continuous solid side walls, for the purpose specified.

37. In a structure of the class described, the combination of a plurality of vertical units or sections formed of concrete, each unit comprising side wall sections connected by cross beams; a concrete bond for the said units uniting them to form practically continuous solid side walls, and a superstructure of concrete molded upon said substructure, whereby said units are further united, for the purpose specified.

38. In a structure of the class described, the combination of a plurality of vertical units or sections formed of concrete, each unit comprising side wall sections connected by cross beams, and a concrete bond for the said units uniting them to form practically continuous solid side walls, for the purpose specified.

39. In a structure of the class described, the combination of a plurality of vertical units or sections formed of concrete, each unit comprising side wall sections connected by cross beams; and means for securing said units to each other.

40. In a structure of the class described, the combination of a plurality of vertical units, or sections formed of concrete, each unit comprising side wall sections connected by cross beams; means for securing said units together; and a superstructure of concrete

molded upon said units, for the purpose specified.

41. In a structure of the class described, the combination with a plurality of integral foundation and superstructure units, formed of concrete, each unit comprising side wall sections connected by cross beams, said side wall sections being extended into foundation piles; and means for securing said units together.

42. In a structure of the class described, the combination of a plurality of integral foundation substructure units or sections formed of concrete, each unit comprising side wall sections connected by cross beams, said side wall sections being extended into foundation piles; means for securing said units together; and a superstructure of concrete molded upon said substructure whereby said units are further united.

43. In a structure of the class described, the combination of integral foundation and substructure units or sections formed of concrete, each unit comprising side wall sections connected by cross beams, said side wall sections being extended into foundation piles; and a superstructure of concrete molded upon said substructure, for the purpose specified.

44. In a structure of the class described, the combination of a plurality of integral foundation and substructure units or sections formed of concrete, each unit comprising side wall sections; and a post connected by crossbeams, said side wall sections and post being extended into foundation piles; and means for securing said units together, for the purpose specified.

45. In a structure of the class described, the combination of a plurality of integral foundation and substructure units or sections formed of concrete, each unit comprising side wall sections and a post connected by cross beams; and means for securing said units together, for the purpose specified.

In witness whereof, I have hereunto set my hand and seal in the presence of two witnesses.

JOHN A. MITCHELL. [L. s.]
Witnesses:

WALTER H. STRAY,
ANNA B. EDWARDS.
